UNITED STATES PATENT OFFICE.

VINCENT BENDIX, OF MEMPHIS, TENNESSEE.

STARTER FOR GAS-ENGINES.

1,144,097.

Specification of Letters Patent. Patented June 22, 1915.

Application filed December 30, 1912. Serial No. 739,168.

To all whom it may concern:

Be it known that I, VINCENT BENDIX, a citizen of the United States, residing at Memphis, in the county of Shelby and State 5 of Tennessee, have invented certain new and useful Improvements in Starters for Gas-Engines, of which the following is a specification.

My invention relates to starters for gas 10 engines and the like and the object thereof is to provide a simple, reliable, automatic device of this character.

Speaking in general terms, my starter comprises a motor of any kind, such as 15 an electric motor capable of operating a rotatable driving member adapted to coöperate with a wheel, such as the usual fly-wheel, driven by the engine, the driving member being arranged to be automatically 20 advanced into coöperative position with the engine wheel when the motor is started and to be automatically withdrawn therefrom when the engine has started. In connection with this construction I may provide an automatic switch controlled by the movements 25 of said member whereby after a manually-operated switch is actuated to start the motor the movement of the member will cause the automatic switch to be closed and 30 the operator thereby relieved from further operation of the other switch.

In the drawings, Figure 1 is a sectional elevation of my device shown in connection with a wheel driven by the engine such as a 35 fly-wheel and showing an electric motor as the motor; Fig. 2 a detail plan of the pinion or worm wheel; Fig. 3 a view similar to Fig. 1 but illustrating a spur gear pinion instead of the worm wheel of Figs. 1 and 2; 40 and Fig. 4 a detail plan view of the pinion of Fig. 3.

In the present instance and by preference, 45 the motor is an electric motor, the driving member a worm gear or a pinion, and also the wheel driven by the engine, the fly-wheel thereof, although it will be understood that my invention in its broader aspect is not to be limited to such motor, gear or pinion or such fly-wheel but that other types of motors 50 and driving connections may be employed and also that the wheel to be driven may be any wheel connected directly or indirectly with the engine so that the movements of the motor and its driving member will start 55 the engine into operation.

In the present instance I have shown two

types of driving connection between the driving pinion and the engine wheel, Figs. 1 and 2 representing worm gearing and Figs. 3 and 4, spur gearing.

Describing the construction shown in Figs. 1 and 2, the engine wheel which is here intended as the fly-wheel 1 of the engine is provided on its periphery with worm teeth 2. The motor comprises an electric motor 65 3, which is here shown as having an extended armature shaft 4, such shaft being in the plane of the engine wheel 1 and in proximity thereto. For a portion of its length this armature shaft is provided with spiral threads 5 with which coöperate corresponding spiral threads in the central opening of the worm wheel or pinion 6 which is adapted to mesh with the teeth 2 of the engine wheel.

The construction and arrangement of the shaft and worm wheel or pinion are such that the latter is capable of an advance movement longitudinal of its shaft upon the initial rotation of such shaft by the electric motor and until the consequent advancement of such worm gear or pinion brings the latter into mesh with the engine wheel whereupon the continued rotations of the shaft rotate the worm wheel or pinion and thereby rotate and drive the engine wheel. Just as soon as the engine itself starts on its own power, the excess rotation of the engine wheel as compared with the degree of rotation of the shaft on which the pinion is mounted (which in the particular instance being described is the armature shaft) will cause the pinion to move laterally (toward the right in Fig. 1), and to be thereby withdrawn from mesh with the engine wheel and to be retracted to idle or normal position.

The motor may be supported in any suitable manner adjacent the engine wheel and in case the device is used in connection with an automobile engine, as herein intended, such support may be a fixed part of the chassis as indicated at 7. The outer or free end of the armature shaft is provided with a suitable bearing 8 in the end of any suitable support such as the bracket 9 which is here shown secured to the body of the motor.

Still referring to the particular mechanism herein shown, the motor is provided with two supply circuits, one being manually operated and the other automatic, although as will be understood the latter may be dispensed with. The manually controlled cir-

cuit comprises the wires 10 and an interposed manually-operated switch shown diagrammatically at 11. In case the device is used in connection with an automobile this switch may be placed upon the dash or elsewhere within easy reach of the driver. The automatic circuit comprises the wires 12 in which is interposed an automatic switch or circuit closer here shown as of the knife type, including the stationary pair of contacts 13, 13 and the movable connector blade 14. This connector blade is one of two arms of a fork (the other being indicated at 15), which are connected to or form a part of a yoke 16 which in turn is carried by the pinion 6 in such manner that the yoke and its connector blade partake of the movements of the pinion or worm wheel longitudinally of the armature shaft. The two arms 14 and 15 are located on opposite sides of the bracket 9 by which they are guided and prevented from rotating when the pinion is rotated. As shown, the yoke fits in a groove 17 at the inner end of the pinion so that such yoke will have longitudinal movement only. The connector or arm 14 is provided with an opening 18 which is adapted to be engaged by a spring catch 19 whose inner end is slightly inturned so as to yieldingly engage said arm in order to hold the pinion in its idle or normal position shown in dotted lines in Fig. 1 but to permit said pinion to be released and to be advanced whenever the electric motor is operated. However, this catch device is not absolutely necessary but may, if desired, be dispensed with.

Describing the operation of my starter and assuming that the pinion 6 is in its retracted position shown in dotted lines in Fig. 1, the first step is the closing of the switch 11 by the driver with the result that the motor 3 is instantly started and its armature shaft 4 rotated. The worm wheel or pinion 6 thereupon moves longitudinally of the shaft, into mesh with the engine wheel and when it is fully in mesh and has reached the end of the threads 5 and abuts against the shoulder 4^a it will rotate in unison with the armature shaft and consequently drive or rotate the engine wheel 1. Inertia of the pinion or friction between it and the yoke 16 should prevent rotation of the pinion until it is in mesh, but a slight rotation thereof before it reaches the engine wheel is immaterial. After the starting of the motor by the push button, the movable connector blade 14 will coöperate with the fixed contacts 13 to close the automatic switch so that the driver or operator may now release the manually operated switch in order to break the circuit which includes the wires 10, the other circuit supplying the necessary current to the motor. This condition obtains until the engine starts under its own power from the

explosions, whereupon the worm wheel or pinion 6 will be withdrawn from mesh with the engine wheel in the manner heretofore described. At a predetermined point in this longitudinal movement of the pinion the contact between the fixed contacts 13 and movable connector blade 14 is broken and the electric motor will thereupon cease to operate. When the worm wheel or pinion returns to its normal position the spring catch 19 will engage the connector blade 14 and hold the pinion in retracted position.

In Figs. 3 and 4 I have shown my invention embodied in a construction in which the teeth on the engine wheel and on the pinion 80 are of the spur type, according to which construction the armature shaft and pinion are arranged in a plane at right angles to the plane of the engine wheel. In these two figures the corresponding parts have the 85 same reference numbers but primed. With the exception of the relative position of parts as just explained and the provision of spur gearing instead of worm gearing the construction and operation is the same as 90 that already described.

It will be understood that, in case the teeth of the engine wheel and pinion are not in proper alinement for meshing, the pinion will abut the teeth on the wheel and owing 95 to this stoppage will be caused to be rotated slightly while being advanced until meshing is obtained.

While I prefer the direct gearing between the armature shaft and the engine wheel and between the motor and the screw shaft, as herein shown and described, yet it will be understood that any suitable indirect gearing or connection may be employed. It will also be understood that the wheel which I 105 have herein referred to as the engine wheel may be the usual fly-wheel or any wheel driven either directly or indirectly by the engine, including, for instance, the transmission in case of an automobile. 110

I claim:

1. A starter for gas engines and the like, comprising in combination with a member operatively connected with the engine, an electric motor including its armature shaft, a screw threaded shaft in line with the armature shaft and driven thereby, a driving member adapted to engage and drive the engine member but normally out of engagement therewith, said driving member being mounted on the screw threaded shaft and having means for engaging the latter whereby operation of the motor advances the driving member into engagement with the engine member. 115 120 125

2. A starter for gas engines and the like, comprising, in combination with a toothed wheel operated by the engine, an electric motor having an extended armature shaft, a pinion mounted thereon for longitudinal 130

and rotary movements relative thereto and adapted to mesh with said wheel, the rotation of the shaft advancing the pinion into mesh with the wheel and the subsequent rotation of the wheel, which exceeds that of the shaft, withdrawing the pinion from mesh.

3. A starter for gas engines and the like comprising, in combination with a toothed wheel operated by the engine, a driving pinion adapted to coöperate with and drive said wheel, a shaft on which said pinion is arranged to have a spiral longitudinal movement relative thereto, a motor operatively connected with the shaft, and means for holding the pinion in retracted position on its shaft.

4. A starter for gas engines and the like comprising, in combination with a toothed wheel operated by the engine, a driving pinion adapted to coöperate with and drive said wheel, a shaft on which said pinion is arranged to have a longitudinal movement relative thereto, a motor operatively connected with the shaft, a spring catch for yieldingly holding the pinion in retracted position.

5. A starter for gas engines and the like comprising in combination with a toothed fly-wheel of the engine, a motor, a driving pinion operated by the motor and adapted

to mesh with and drive said wheel but normally out of engagement therewith, and means whereby relative movement between the motor and pinion automatically moves the latter into driving engagement with the wheel.

6. A starter for gas engines and the like comprising, in combination with a wheel operatively connected with the engine and having worm teeth, a motor, a worm operated by the motor and adapted to mesh with said worm teeth but normally out of engagement therewith, and means whereby relative movement between the motor and the worm automatically moves the latter into driving engagement with said worm teeth.

7. A starter for gas engines and the like comprising, in combination with a wheel operatively connected with the engine and having worm teeth, a motor, a shaft driven by the motor, and a worm mounted in and having screw threaded engagement with the shaft for longitudinal movement relative thereto whereby when the shaft is rotated the worm is automatically moved into mesh with said teeth.

VINCENT BENDIX.
